UNITED STATES PATENT OFFICE.

EDWARD VERMYLIAN RUNION, OF SELMA, CALIFORNIA.

OIL-CAN.

SPECIFICATION forming part of Letters Patent No. 372,332, dated November 1, 1887.

Application filed August 21, 1887. Serial No. 245,972. (Model.)

To all whom it may concern:

Be it known that I, EDWARD VERMYLIAN RUNION, a citizen of the United States, residing at Selma, in the county of Fresno and State of California, have invented a new and useful Improvement in Oil-Cans, of which the following is a specification.

My invention relates to improvements in oil-cans adapted for use in oiling machinery, whereby oil may be easily forced through a long discharge-tube to put any desired amount of oil in a journal or oil-cup by a single motion of the oil-ejecting device.

In the drawings, Figure 1 is a vertical central section. Fig. 2 is a similar view with the reservoir forced up, as seen in discharging oil.

Referring to the drawings by letter, A designates the body or outer shell of the oiler, having an inner vertical flange, B, soldered to 20 and extending up from the lower edge, and C is the reservoir, having an outer downwardly-extending flange, D, from the upper edge thereof. The said flange D is adapted in size to pass down into the groove formed between 25 the flange B and the outer shell of the oiler.

E designates an inturned flange soldered on the upper edge of the reservoir, for a purpose hereinafter described.

G designates a cap secured to the upper end 30 of the outer shell by soldering or otherwise.

H is the discharge-tube, and I is a screw-coupling between the said cap and the tube.

K designates an inwardly-extending flange secured in the cap G, and L is a spiral spring 35 bearing at the ends against the under side of the flange K and the upper side of the flange E, before mentioned.

It will be seen that the tendency of the spring is to force the reservoir down and hold 40 it normally at the extreme limit of motion thereof, and after the said reservoir has been pressed up to eject oil and is again released the spring will return the same to its normal position.

By constructing the oiler as herein described 45 no oil can escape from the reservoir and find its way out through the lower end of the shell, for the parts all slide tightly together, and in order that oil may escape it must pass down

around the outer flange of the reservoir, and 50 thence rise over the inner flange of the outer shell and pass down between the said flange and the inner wall of the reservoir. The few drops of oil which will work out will only serve to lubricate the rubbing surfaces of the 55 movable parts.

The advantage gained by constructing the device so that the entire reservoir may be pushed up to eject the oil is that in this way the discharge of the oil is made more certain; 60 also, any desired quantity of oil may be ejected at one pressure, governed by the distance that the said reservoir is pressed up, it being evident that the said reservoir may be pressed up as slight a distance as the ordinary spring- 65 bottom in oilers now in use; also, the discharge of the oil by this device is very steady and regular, as the pressure upon the bottom of the reservoir may be as slow as desired, and thus eject the oil in a steady stream. 70

Having thus described the construction, operation, and advantages of my invention, I claim—

1. An oiler comprising the outer shell, A, having discharge-tube H and vertical inner 75 flange, B, secured to its lower edge, and reservoir C, having an outer flange depending from the upper edge thereof and adapted to engage over the flange secured to the shell, substantially as set forth. 80

2. An oiler comprising the outer shell, A, having discharge-tube H and the upturned inner flange, B, the reservoir C, having the inwardly-projecting flange, E, at its upper end and the outer flange, D, depending from the 85 said flange E and adapted to engage over the inner flange of the shell A, the inwardly-projecting flange K in the upper end of the shell A, and the spiral spring arranged between the flanges E K, substantially as and for the purposes set forth. 90

In testimony that I claim the foregoing as my own I have hereto affixed my signature in presence of two witnesses.

EDWARD VERMYLIAN RUNION.
